DESIGN FOR A HANDKERCHIEF

Helen Sargent Hitchcock, New York, N. Y.

Application September 15, 1937, Serial No. 71,634

Term of patent 3½ years

To all whom it may concern:

Be it known that I, Helen Sargent Hitchcock, a citizen of the United States of America, residing in city of New York, county of New York, and State of New York, have invented a new, original, and ornamental Design for a Handkerchief, of which the following is a specification, reference being had to the accompanying drawing, forming part thereof.

The figure on the drawing is a plan view of a handkerchief embodying my new design.

I claim:

The ornamental design for a handkerchief substantially as shown.

HELEN SARGENT HITCHCOCK.
